United States Patent Office.

T. B. FAGAN, OF MENDON, OHIO.

Letters Patent No. 78,198, dated May 26, 1868.

IMPROVEMENT IN DITCHING-MACHINES.

The Schedule referred to in these Letters Patent and making part of the same.

TO ALL WHOM IT MAY CONCERN:

Be it known that I, T. B. FAGAN, of Mendon, in the county of Mercer, and State of Ohio, have invented certain new and useful Improvements in Ditching-Machines; and I do hereby declare that the following is a full, clear, and exact description thereof, reference being had to the accompanying drawings, and to the letters of reference marked thereon, which form a part of this specification, in which—

Figure 1 represents a side elevation, and

Figure 2 a plan view of my ditching-machine.

The nature of this invention consists in the employment of certain new and useful devices, to be used in connection with a ditching-machine, when constructed and arranged substantially in the manner, and for the purpose hereinafter set forth.

To enable others skilled in the art to make and employ my invention, I will now describe its construction and operation.

A designates the platform or body of the machine, which is mounted upon the rear axle of the wheels B' B', said wheels being furnished or cast with projections on their periphery, as seen in figs. 1 and 2, in order to allow them to adhere to the soil. B B designate the front wheels, which are mounted upon an axle, said axle being secured to the rear axle by means of the coupling-pole d. c represents the tongue, attached to the front axle in the ordinary way. Working on the axle of the wheels B' B' are also the inside cog-wheels C C, which will be referred to hereafter. D D represent two semicircular supports or arms, having one-half of their surface above and one-half below the platform A, and firmly secured thereto, (see fig. 1.) Secured to the outer surface of these arms, by means of bolts, are two clips or eyes e e, into which the shaft J revolves, said shaft being provided at each end with a pinion, j, which gears with the inside cog-wheels C C. The arms or supports D D are also furnished with additional holes, the object of which will be apparent hereafter. F designates the revolving ditching-wheel, which is supplied with the shovels b b, formed as represented in fig. 1. Said wheel is adjusted upon the shaft J by means of a screw, and may be raised or lowered as the case may require, by adjusting the clips e e to the holes in the supports B B, already described. E represents a chute, furnished with the inclined side pieces f f, the inner ends of said pieces being attached to the upper part of the arms or supports D D by means of screws, as seen in fig. 2. The object of said arrangement is to prevent the dirt, after leaving the shovels of the ditching-wheel, from falling into the ditch while being excavated. G represents a staple-like device, adjusted to the coupling-pole d. The lower ends of said device are rounded and made sharp, in order to assist in cutting the ditch, and will also clear the ground, over which the ditching-wheel is to pass, of stones or any obstacles that may be in the way.

This device is furnished with holes also, for the purpose of allowing it to be adjusted to suit the elevation of the ditching-wheel, and is intended to be made of steel.

It will also be remarked that this device will prevent the ditcher from being cramped while passing over the ditch a second time.

What I claim as new, and desire to secure by Letters Patent, is—

1. In combination with the wheel F, the arms or supports D D, provided with adjustable holes, as and for the purpose described.

2. In combination with wheel F and supports D D, I claim the chute E, constructed and employed substantially as and for the purpose specified.

3. The combination of the ditching-wheel F, chute E, supports or arms D D, and shaft J, furnished with pinions j j, arranged and operating substantially in the manner and for the purpose set forth.

In testimony that I claim the foregoing as my own, I affix my signature in presence of two witnesses.

T. B. FAGAN.
